[57] CLAIM

The ornamental design for a distancing clip for drapes or sunblinds, as shown and described.

DESCRIPTION

FIG. 1 is a perspective view of a distancing clip for drapes or sunblinds showing my new design;

FIG. 2 is a front end view thereof;

FIG. 3 is a top plan view thereof;

FIG. 4 is a right side elevational view thereof;

FIG. 5 is a bottom plan view thereof;

FIG. 6 is a left side elevational view thereof; and,

FIG. 7 is a rear end view of FIG. 5.

The holder is shown broken away in FIGS. 1 and 3-6 to indicate indeterminate length.

FIG. 1

FIG. 2

FIG. 3

FIG. 4

FIG. 5

FIG. 6
